(57) **CLAIM**

The ornamental design for a vehicle clearance crossmember support bracket, as shown and described.

DESCRIPTION

FIG. 1 is a rear perspective view of vehicle clearance crossmember support bracket showing my new design;

FIG. 2 is a front perspective view thereof;

FIG. 3 is a rear elevational view, the front elevational view being a mirror image thereof;

FIG. 4 is a front elevational view, the rear elevational view being a mirror image thereof;

FIG. 5 is a left side elevational view, the right side elevational view being a mirror image thereof;

FIG. 6 is a right side elevational view, the left side elevational view being a mirror image thereof;

FIG. 7 is top plan view thereof; and,

FIG. 8 is a bottom plan view thereof.

The claimed vehicle clearance crossmember support bracket is used to raise the chassis of a vehicle.
